UNITED STATES PATENT OFFICE.

WILLIAM SHEAHAN, OF OCEAN FALLS, BRITISH COLUMBIA, CANADA; LAMAR TOOZE, ADMINISTRATOR OF SAID WILLIAM SHEAHAN, DECEASED, ASSIGNEE TO JOSEPH W. SHEAHAN, OF LOS ANGELES, CALIFORNIA, AND MARIE B. TOOZE, OF EUGENE, OREGON, AND EDWARD K. SHEAHAN, OF LOS ANGELES, CALIFORNIA, AND LOUISE M. SHEAHAN, OF EUGENE, OREGON, JOINTLY.

PAPER-MAKING MACHINE.

Application filed August 29, 1921. Serial No. 496,794.

To all whom it may concern:

Be it known that I, WILLIAM SHEAHAN, a citizen of the United States, and a resident of the city of Ocean Falls, Province 5 of British Columbia, Dominion of Canada, have invented a certain new and useful Improvement in Paper-Making Machines, of which the following is a specification.

This invention relates to the process of 10 manufacturing paper by machines. As well known, such machines comprise press-rolls, by which the water is pressed out of the web of paper, and drier rolls or "driers"; and the web has to be carried to said press-rolls 15 and from these to the driers.

Heretofore, it required a skilled attendant at each of the press rolls whose duty it was to guide the lead end of the web of paper by hand, to said rolls. Such work 20 involved some danger to the attendant, also involved loss of time, and waste of paper. The web of paper being moist, the leading end has a tendency to cling to one of the rolls between which it passes, if there are 25 no guiding means.

The object of my invention is to provide 30 mechanical means by which the said lead end of the web is guided to and thru the press rolls to the driers.

I attain my object by means of companion 35 ropes or carriers travelling in contact with each other, and extending to and between the rolls, over and between which the lead end of the web of paper is to be guided.

At the receiving end of the first set of press 40 rolls, these carriers are spaced apart so as to facilitate the insertion between of said lead end of the web, and a little farther on the carriers are brought into contact with each other, so as to grasp and hold the lead 45 end, and in that way carry and guide the same thru the press rolls to the driers.

Other uses and applications of my invention 50 will suggest themselves.

In the accompanying drawings, I have 55 diagrammatically illustrated the practical application of my invention, the figures showing as follows:

Figs. 1 and 2 represent end sections of a 60 paper making machine, the views showing two sets of press-roll, and one of the drier rolls; and

Fig. 3 is a fragmentary diagrammatic view of those ends of the press rolls adjacent the ropes or carriers, the upper roll 55 being shown in section and the lower in side elevation; and this view shows the means provided on the projecting end of the upper roll for guiding the carriers past these press rolls, and so as to cause the carriers to travel 60 at the same rate as the web of paper.

In describing the devices shown in the drawings, I will refer only to those parts which deal directly with my invention. The views shown represent parts of a machine 65 of standard construction, therefore well known to all conversant with the paper making art.

a and *b* represent one set of press rolls, 70 and *c*, *d* represent another set of press rolls, it being understood that the machine may have any number of sets of press rolls. The line *e* represents the felt running thru the machine. *f* and *g* are the two endless ropes or carriers by which the lead end of the web 75 of paper, designated by the broken line *q* in Fig. 1, is conducted to and between the press rolls, and finally to the means, such as ropes *h*, for example, by which the web of paper is conducted to the drier rolls. 80

At the receiving end of the machine shown in Fig. 1 the carriers *f* and *g* run over sheaves *i* and *j*, which are arranged to guide the carriers side by side along one edge of the web of paper, but these sheaves are vertically spaced apart so as to separate the receiving ends of the carriers and permit the placing of the web of paper between them, as diagrammatically illustrated by the broken line *q* in Fig. 1. A short distance 85 beyond the sheaves *i* and *j* is provided another sheave *r*, for supporting the carriers *f* and *g* the latter converging to that point, in so doing gripping and holding the lead end of the web of paper, and pulling and 90 guiding the same thru the first set of press rolls *a* and *b*.

In order to guide the web of paper towards the press rolls it is only necessary to seize and hold one edge thereof, this 100 end of the web being usually torn diagonally across.

The upper press roll *a* is provided at one end with a sheave element consisting of a

flanged guide ring y seated on ball bearings z mounted on said end as shown in Fig. 3. The flanged ring y serves as a guide for the carriers f and g as illustrated in Fig. 3, since the strain on said carriers tends to hold them against the upper roll a .

The carriers f and g pass from the first set of press rolls to the second set c , and d , as illustrated in Fig. 2, running over sheaves s , t , u , to said second set of press rolls, the upper c of which is also provided with guiding means for the carriers like those shown in Fig. 3. The means provided on the upper of the press rolls for guiding the carriers must be adapted to cause the latter to travel at the same speed as that at which the web of paper is traveling.

From the second press rolls c , d , the carriers pass over sheave w to the drier roll x , at which point the carriers are carried over a pair of sheaves 3 , which are arranged to separate the carriers laterally so as to release the lead end of the web of paper. The lead end of the web of paper having arrived at the drier roll x is then seized by the other guide ropes or carriers h by which the lead end is carried over the drier roll x and the drier roll x' .

h' shows another of the carriers carrying the lead end of the web of paper over the drier rolls. The latter carriers are arranged substantially as shown in my Letters Patent of the United States reissued June 8, 1915, No. 13,925, entitled Improvement in drier rolls for paper making machines.

From the sheave 3 the carriers f and g pass over the sheave p , which is assumed to be driven by being connected thru the medium of a clutch with a suitable driving mechanism all of which details are readily understood and therefore are not described.

The carriers run over the sheave p to the sheave o , thence over tightening devices such as shown by m , n , l in Fig. 1; and from the sheave l of the latter devices the carriers run over sheave k back to the sheaves i and j .

When the lead end of the web of paper has reached the drier roll x the driving of the sheave p —which drives the carriers—may be discontinued by throwing out the clutch of the sheave p until the carriers f and g are again required to be thrown into action.

I claim:

1. In a paper making machine, in combination with the press-rolls of means for conducting the web of paper thereto, such means comprising a sheave element mounted on the periphery of one end of the upper press-roll, a pair of endless travelling carriers bearing in said sheave element, side by side, the carrying surface of said sheave element being below the web carrying surface of said press-roll by the thickness of said carriers, so that the web-carrying surfaces of said carriers

faces of the latter will travel approximately at the same speed as said drier-rolls, sheaves arranged for conducting said carriers to and from said press-rolls, the sheaves in front of the latter being adapted to separate said carriers at the web receiving end so as to permit the lead-end of the web to be placed between them.

2. In a paper making machine, in combination with the press-rolls of means for conducting the web of paper thereto, such means comprising, a ball-bearing mounted on the periphery of one end of the upper press-roll, a guide-ring seated on said ball-bearing, a pair of endless travelling carriers bearing in said guide-ring, side by side, the carrying surface of said guide-ring being below the web carrying surface of said press-roll by the thickness of said carriers, so that the web-carrying surfaces of the latter will travel approximately at the same speed as said drier-rolls, sheaves arranged for conducting said carriers to and from said press-rolls, the sheaves in front of the latter being adapted to separate said carriers at the web receiving end so as to permit the lead-end of the web to be placed between them.

3. In a paper making machine, in combination with the press-rolls of means for conducting the web of paper thereto, such means comprising, a ball-bearing mounted on the periphery of one end of the upper press-roll, a flanged guide-ring seated on said ball-bearing, a pair of endless travelling carriers bearing in said guide-ring, side by side, the carrying surface of said guide-ring being below the web carrying surface of said press-roll by the thickness of said carriers, so that the web-carrying surfaces of the latter will travel approximately at the same speed as said drier-rolls, sheaves arranged for conducting said carriers to and from said press-rolls, the sheaves in front of the latter being adapted to separate said carriers at the web receiving end so as to permit the lead-end of the web to be placed between them.

4. In a paper making machine, in combination with the press-rolls of means for conducting the web of paper thereto, such means comprising, a sheave element mounted on the periphery of one end of the upper press-roll, a pair of endless travelling carriers bearing in said sheave element, side by side, the carrying surface of said sheave element being below the web-carrying surface of said press-roll by the thickness of said carriers, so that the web-carrying surfaces of the latter will travel approximately at the same speed as said drier-rolls, sheaves arranged for conducting said carriers to and from said press-rolls, the sheaves carrying the carriers to the press-rolls comprising of a pair vertically spaced, so as to separate the carriers at this point and permit the lead-end

of the web to be placed between them, and another sheave adapted to carry both carriers side by side, the latter sheave being located directly in front of said upper press 5 roll relatively to said guide-ring and so as to cause the carriers to bear up against said guide ring.

5. In a paper making machine, in combination with the press-rolls of means for 10 ducting the web of paper thereto, such means comprising, a ball-bearing mounted on the periphery of one end of the upper press-roll, a guide-ring seated on said ball-bearing, a pair of endless travelling carriers bearing in said guide-ring, side by side, the carrying surface of said guide-ring being 15 below the web - carrying surface of said press-roll by the thickness of said carriers, so that the web-carrying surfaces of the latter will travel approximately at the same 20 speed as said drier-rolls, sheaves arranged for conducting said carriers to and from said press-rolls, the sheaves carrying the carriers to the press-rolls comprising of a pair vertically spaced, so as to separate the carriers at this point and permit the lead-end 25 of the web to be placed between them, and another sheave adapted to carry both carriers, side by side, the latter sheave being located directly in front of said upper press 30 roll relatively to said guide ring, and so as to cause the carriers to bear against said guide-ring.

WILLIAM SHEAHAN.
